UNITED STATES PATENT OFFICE

HARRY H. FERRIS, OF HUNTINGTON BEACH, CALIFORNIA.

COMBINATION-JACK.

1,083,816.

Specification of Letters Patent.

Patented Jan. 6, 1914.

Application filed April 25, 1913. Serial No. 763,602.

To all whom it may concern:

Be it known that I, HARRY H. FERRIS, a citizen of the United States, residing at Huntington Beach, in the county of Orange and State of California, have invented new and useful Improvements in Combination-Jacks, of which the following is a specification.

The present invention relates to devices 10 adapted for use in the track construction of railways and which may be termed a combination jack.

In carrying out my invention, it is my purpose to provide a tool or instrument 15 wherein tracks may be properly gaged or brought into proper alinement by a tool constructed in accordance with my invention, and operated by a single hand, and furthermore, to provide a tool of this class 20 wherein the rails may be properly gaged and the tie raised to permit of the rail securing spikes being attached thereto without the employment of a separate device for this purpose.

25 With the above recited objects in view, and others which will appear as the nature of the invention is more fully understood, the improvement resides in the construction, combination and operative arrangement of 30 parts set forth in the following description and falling within the scope of the appended claim.

In the drawing: Figure 1 is a top plan view illustrating my improved jack in position 35 upon a pair of rails, Fig. 2 is a front elevation of same, the rails being shown in section, Fig. 3 is a side elevation of the same, and Fig. 4 is a similar view, parts being broken away, and illustrating the method 40 of raising a tie to permit of the rails being spiked thereon.

My improved jack comprises essentially a body member 1 which is preferably arched, and which in cross section, is preferably 45 substantially T-shaped. The body 1 has its opposite ends each provided with oppositely curved arms 2 and 3 respectively, the said arms terminating in shouldered fingers 4 which are arranged in a plane equaling the 50 plane of the longitudinal sides of the body. The shoulders of the fingers 4 are adapted to engage with the inner faces of the rails R, while the fingers proper overlie the said rails. The shoulders of the arms 2 and 3 55 upon the opposite ends of the body are ar-

ranged a distance away from each other equaling the proper spacing distance between the rails R or the said shoulders provide a proper gage for the rails R. The body 1 has its upper edge centrally provided 60 with spaced lugs 5, between which is pivotally connected, as at 6, a lever 7. The lever 7 has one of its ends provided with a pair of links 8 which are pivotally connected to the ends of a pair of tongs 9. The tongs 9 65 are adapted to have their toothed ends engage with the tie T, which, after the rails R have been properly gaged by the improved jack, may be lifted by a pressure upon the lever 7 to bring the said tie into a position 70 to be spiked to the rails R.

By reference to the figures of the drawing, it will be noted that the arms 2 are arranged nearer the body 1 than are the arms 3, and the tongs 9 being disposed between the said 75 arms 2, but to the rear of the shoulders and fingers of said arms, will not have a tendency to tilt the jack when the tongs are employed for elevating a tie.

From the above description, taken in connection with the accompanying drawings, the simplicity of the device, as well as the advantages thereof, will it is thought, be perfectly apparent to those skilled in the art to which such inventions appertain without 85 further description.

Having thus described the invention, what I claim as new is:

In a combined tie jack, an arched body having its ends provided with oppositely 90 curved arms terminating in shouldered fingers that are arranged in a plane parallel to the longitudinal sides of the body, the arms upon one of the sides of the body terminating at a lesser distance from the body 95 than the arms upon the opposite side of the body, the body being centrally provided with upturned lugs, a lever pivotally secured between the lugs, a pair of links pivotally connected with the lever, and each of said links 100 being pivotally connected with the arms of pivoted tongs beyond the pivots of said tongs.

In testimony whereof I affix my signature in presence of two witnesses.

HARRY H. FERRIS.
